POWDER PUFF

Albert E. Vaughn, Los Angeles, Calif.

Application October 29, 1941, Serial No. 416,953

6 Claims. (Cl. 15—131.1)

The present disclosure is a continuation-in-part of my copending application Serial No. 375,821, filed January 24, 1941.

My invention relates to flexible envelopes containing finely divided powder and more particularly to such envelopes designed for progressively dispensing or applying a powder-like material. The invention is applicable in various arts to dispensing various finely divided materials but is being initially embodied in a dispensing powder puff. For the purpose of this disclosure the invention will be described as so embodied, it being apparent that such a disclosure will be adequate guidance for those skilled in the art who may need to apply the invention to other devices for other purposes.

The general object of the instant embodiment of the invention is to produce an efficient powder-containing puff, a powder puff that is economical in consumption of powder, simple in construction, and inexpensive to manufacture.

The procedure of dipping a simple powder puff of the prevalent type into a mass of loose powder is wasteful and does not favor uniform application of powder to the skin. The fabric of the conventional powder puff, moreover, tends to become soiled rapidly and if brought into contact with oleaginous substances, such as face cream, powder foundation, or even the natural oils of the skin, tends to become matted and "slicked up." The outstanding advantage of the prevalent simple powder puff, however, is that with reasonable care the powder applied thereby may be restricted substantially to the selected areas of application. It is not difficult to avoid throwing powder particles into the air in random directions, the uncontrolled particles being inhaled or alighting on the user's hair, eyeglasses or clothing.

The desirability of a powder puff enclosing its own supply of powder for release through a powder-pervious wall has long been recognized. It is well known that such a powder-containing puff can minimize waste and simplify the powder-applying procedure. Certain difficulties, however, have prevented any widespread acceptance of the powder-dispensing puffs that have heretofore been offered to the public. One of these problems is to obtain release of the powder at an economical yet satisfactory rate without the necessity of patting the puff against the skin and thereby throwing powder particles in random directions. Another and related problem is to maintain a desired rate of powder release throughout the service life of the puff. A dispensing powder puff may function efficiently at first but only for a short service period. A conventional powder puff may be serviceable in spite of substantial matting of its fibers, but if the fibers of a powder-dispensing puff are matted and embedded the powder supply is cut off. With pro-

gressive clogging of the paths of powder release provided in powder-dispensing puff, it becomes necessary to pat the puff with increasing violence to release powder and the puff may become entirely useless before the powder supply is exhausted.

Important objects of the present invention are to provide a powder-containing puff that will release its powder content at a desired rate and to provide a powder-dispensing puff that will maintain its utility and desirable capabilities substantially undiminished over a long service period, the service life of the puff terminating only when the original powder supply is exhausted.

15 In the attainment of these important objects it has been necessary to meet the problems and difficulties mentioned heretofore, and a feature of my invention is the concept that these problems and difficulties may be met by employing 20 a velvet-like dispensing sheet having a pile of fibers that are smooth-surfaced, resilient, and in a special sense non-absorbent. I have discovered that a pile of extruded fibers of synthetic material, such as a rayon pile, has certain properties or characteristics affording peculiar advantages of importance in a powder puff. Further objects of the invention include 25 the attainment of these advantages, detailed discussion of the advantages being reserved for a later point in the disclosure.

30 After face powder dispensed from a supply container is applied to the skin, it may be desirable to employ some suitable auxiliary means to spread or blend the applied powder. A further object of my invention is to provide a powder-dispensing puff having a non-dispensing portion to serve as a manually operable spreading or blending means. In this regard the preferred form of my invention is characterized by the 35 concept of a dispensing envelope with a pliant marginal flap, which flap includes a portion of the dispensing fabric to provide a desirable spreader surface of the flap. One feature of the invention is the provision of outwardly extending resilient fibers on a marginal flap to serve as a brush for spreading powder.

40 The above and other objects and advantages will be apparent in my detailed description to follow, taken with the accompanying drawing.

45 In the drawing, which is to be considered as illustrative only:

Fig. 1 is a perspective view of the preferred 50 form of the new powder puff;

Fig. 2 is a plan view of the puff;

Fig. 3 is a bottom view of the puff;

Fig. 4 is a transverse section of the puff on an 55 enlarged scale;

Fig. 5 is an enlarged portion of Fig. 4;

Fig. 6 is a view similar to Fig. 4 showing an 60 alternative construction for the puff; and

Fig. 7 is an enlarged portion of Fig. 6.

Figs. 1 to 5 show a container or envelope in which a mass of face powder 10 is confined in a pocket between a dispensing wall or sheet generally designated 11 forming one side of the envelope and a foundation wall or sheet generally designated 12 forming the other side of the envelope. The dispensing sheet 11 comprises a velvet-like fabric having a base weave 13 sufficiently loosely woven to release the powder at a desired rate and having an outwardly presented pile 15. The individual fibers of the pile 15 are smooth, resilient, and have characteristics and capabilities to be discussed later. In the present practice the pile 15 is rayon.

Preferably the pocket containing the mass of powder 10 is formed substantially entirely in the dispensing sheet 11, the dispensing sheet being pre-stretched to the required concave configuration indicated in the drawing. It is contemplated that the pocket will be of liberal capacity, the initial depth of the pocket being greater than the combined thicknesses of the two sheets 11 and 12.

Marginal portions of the two sheets 11 and 12 lie together to form a marginal flap 16 for the powder-containing envelope, which flap is preferably continuous around the circumference of the envelope. The two overlapping marginal portions of the sheets 11 and 12 are united by suitable means, for example by intervening adhesive. In the particular construction shown in the drawing the pile 15 of the upper sheet 11 is crushed in an inner ring or inner zone 17 of the marginal flap 16, in which zone the two sheets are tightly bonded together to form an effective powder-tight seal. In an outer zone 18 of greater radial width the two sheets are only lightly bonded together, the pile fibers in this outer zone standing out resiliently to provide a short, pliant, annular brush around the envelope.

The foundation sheet 12 is intended to be impervious with respect to the powder particles and preferably is sufficiently flexible and pliant for suitably yielding action when the puff is applied to the skin and yet the foundation sheet is stiff enough to lie substantially flat and resist crumpling or folding. Powder puffs constructed in the general manner herein indicated commonly crumple or sag into wrinkled state when placed on edge, especially during transportation in a handbag. One object of the present construction is to provide a powder puff that will maintain the desired configuration under all normal circumstances. In addition to attaining a desirable compromise between a desirable flexibility in the marginal flap 16 and a desirable degree of stiffness in the foundation sheet to resist crumpling, it is also requisite that the marginal flap have a certain substantial thickness or body.

In the particular construction exemplified in Figs. 1 to 5, the foundation sheet 12 is a velvet-like fabric with a downwardly extending pile 20, the fabric being, for example, cotton velure. A feature of the illustrated construction is the employment of an adhesive coating 21 over the entire inner face of the sheet 12 to serve three separate functions, namely, to seal the interstices of the foundation sheet thereby to make the foundation sheet impervious to the powder, to form a bond between the sheets 11 and 12 in the areas where the two sheets lie together forming the marginal flap 16, and to cooperate with the two sheets 11 and 12 to provide the desired degree of flexibility for the marginal flap. In practice I use rubber cement for the adhesive coat because rubber cement both seals the pores of the cotton velure and

5 unites the marginal portions of the two sheets together and yet remains pliable throughout the service life of the powder puff. An ordinary adhesive, such as common glue, would not be satisfactory because it dries to a stiffness that would destroy the usefulness of the marginal flap.

10 Figs. 6 and 7 show a powder puff of substantially the same construction as described above, corresponding numerals designating corresponding parts. The second construction differs from the first only in having a foundation sheet generally designated 22 that is made of what may be termed a porous lastic. By porous lastic is meant rubber or rubber substitutes fabricated with numerous air cells. The foundation sheet 22 in the drawing may be sponge rubber or airfoam rubber, the inner face of the sheet being sealed with the usual adhesive coating 21. Porous lastic material has a fortuitous combination of properties for the present purpose. The sheet may be thick enough to give body to the marginal flap 16 and yet be sufficiently flexible and yielding to serve as the major part of a powder-spreading device for application to the skin. Of further importance is the fact that a porous lastic sheet has inherently the desired resistance to crumpling and folding.

15 In service the powder puff is pressed and rubbed lightly against the skin to cause the powder to work outwardly through the dispensing sheet and to cause the powder to be applied over the desired 20 area. In response to simple wiping pressure the powder is released at a satisfactory rate and yet so economically that such a powder puff packed with only a moderate quantity of powder has a relatively long life of service. The fact that the foundation sheet 12 is not pervious to the powder prevents powder from being released onto the user's hand or being otherwise wasted. After the initial operation of applying the powder, the marginal flap of the powder puff is employed as a wiping means to spread and blend the powder. In practice the spreading operation is easily performed without further release of powder to any undesirable degree.

25 30 35 40 45 50 55 The utility of the new powder puff largely depends, as heretofore noted, on the structure and character of the dispensing sheet through which the powder is released and by means of which the powder is applied to the user's skin. The advantages of employing a velvet dispensing sheet with a pile of extruded fibers of synthetic material, such as rayon, are as follows:

60 65 70 75 80 85 1. Extruded fibers of synthetic material as distinguished from vegetable fibers (cotton velure) and animal fibers (wool and silk) are relatively smooth so that powder particles do not tend to cling to them tenaciously. There is relatively little frictional resistance to the outward movement of powder through passages formed by rayon fibers. Powder particles flow so easily through rayon pile that release of the powder at a desirable rate may be accomplished simply by rubbing the powder puff lightly across the skin, there being no necessity whatsoever to pat the puff against the skin. No particular care is required to restrict the powder application to desired areas.

85 90 95 2. Synthetic extruded fibers of the character of rayon have less affinity for skin oils and other oils than exist between powder particles and such oils. Apparently cotton, silk and wool fibers have an affinity for oils comparable to that of powder particles.

3. Synthetic fibers, such as rayon, are relatively non-absorbent with respect to oil and do

not soften and lose resiliency in the presence of oils. Animal and vegetable fibers on the contrary tend to become soggy and lifeless when in contact with oils.

4. Pile fibers of rayon and the like not only tend vigorously to stand out from the woven base of the velvet fabric even after being subjected to considerable pressure, but also withstand continual bending without fatigue. Silk and cotton fibers, on the other hand, lack such resiliency and may be easily crushed permanently. In fabricating the powder puff hereinbefore described, application of pressure is necessary to cause adhesion of the two fabric sheets to form the unitary marginal flap of the powder puff. The rayon fibers immediately recover from that pressure, whereas other fibers commonly employed for a velvet pile would be permanently damaged.

5. Because pile fibers of rayon and the like are relatively smooth and have little affinity for oils, the fibers have a characteristic that may be described as lack of any tendency to become matted by oleaginous mixtures. In contrast, pile fibers of silk and cotton tend to become permanently embedded in masses of intermixed oils and powder.

A dispensing sheet of velvet having a pile of rayon or the like may be described as "self-cleaning," since the powder particles moving outward through the rayon fibers carry away contaminating substances. Such a dispensing sheet is not, of course, contamination-proof and does become soiled in the course of normal service, but the cleaning action of the outwardly flowing powder particles is effective to an important extent and markedly retards the rate at which the soiling of the dispensing sheet progresses. If rayon pile is used for a simple non-dispensing powder puff the pile becomes soiled and matted in a relatively short period of service. It is apparent, then, that the outward flow of powder particles through the rayon pile of a dispensing powder puff is of prime importance in retarding contamination of the pile. The so-called self-cleaning action of rayon pile in a dispensing sheet as contrasted with the action of silk and cotton pile may be demonstrated by making experimental powder puffs with various materials for the dispensing sheets and then rubbing into the pile of each experimental powder puff a liberal quantity of a grease such as vaseline or of an oleaginous mixture such as an ordinary powder base. The foreign matter will work free of the rayon fibers and disappear in a short period of normal service, but will stubbornly remain in the pile fibers of silk and cotton.

The detailed description herein of the preferred forms of my invention will suggest various changes and substitutions under my inventive concept; I reserve the right to all such departures from the described devices that properly come within the scope of my appended claims.

I claim as my invention:

1. A dispensing envelope for powdered material having: a dispensing wall of fabric forming one side of the envelope, said fabric being sufficiently loosely woven to permit the powder particles to filter through, said fabric having an outwardly presented pile of resilient fibers of synthetic material; and a flexible wall of material impervious to the powder particles forming the other side of the envelope, the marginal portions of said

two walls combining to form a margin of the envelope for use as a means to spread released powder, said two walls being heavily bonded together along an inner zone of said spreading margin to seal the powdered material in the envelope, said two walls being lightly bonded together in an outer zone of said spreading margin with said pile fibers resiliently standing out in said outer zone to form a powder brush.

10. 2. A dispensing envelope as set forth in claim 1 in which said spreading margin is continuous around the envelope and in which said inner zone of the spreading margin is relatively narrow and said outer zone is relatively broad.

15. 3. A dispensing envelope for powdered material having: a dispensing sheet of fabric forming one side of the envelope, said fabric being pervious to said powdered material and having an outwardly presented pile of smooth fibers of synthetic material; and a flat foundation sheet of elastic material forming the other side of the envelope, said foundation sheet being sufficiently thick to resist crumpling or folding.

20. 4. A dispensing envelope for powdered material having: a dispensing sheet of fabric forming one side of the envelope, said fabric being pervious to said powdered material and having an outwardly presented pile of fibers of synthetic material; a flat foundation sheet of porous elastic material forming the other side of the envelope, said foundation sheet being sufficiently thick to resist crumpling or folding;

25. 30. 5. A dispensing envelope for powdered material having: a first sheet of velvet with an outwardly extending pile of smooth synthetic fibers, said sheet forming one side of the envelope and being loosely woven to permit the powder particles to filter through, said sheet being of bulging configuration to form a powder pocket; a second sheet of flexible pervious material forming the other side of the envelope, marginal portions of said two sheets lying together to form a relatively wide margin for the envelope serviceable as means to spread released powder; and a coating of cement on the inner face of said second sheet,

35. 45. 60. 50. 55. 65. 70. 75. 80. 85. 90. 95. 100. 105. 110. 115. 120. 125. 130. 135. 140. 145. 150. 155. 160. 165. 170. 175. 180. 185. 190. 195. 200. 205. 210. 215. 220. 225. 230. 235. 240. 245.
